ROTARY MACHINE FOR COMPACTING
LOOSE MATERIAL TO SOLID PRISMATIC LUMPSJean Louis Chambon, Paris, France, assignor to
Societe d'Etudes de Machines Speciales, Paris,
FranceApplication January 19, 1950, Serial No. 139,523
In France January 27, 1949

5 Claims. (Cl. 107—8)

1

Machines designed to compact loose material to solid prismatic lumps are known which comprise a rotary drum formed with radial cavities into which charges of the loose material are to be introduced successively, compacting pistons which are reciprocated in said cavities by means of central cams and lids to close said cavities once filled with the loose material during the compacting step.

My invention relates to a machine of the kind just referred to which is designed especially for the mass production of prismatic lumps of comparatively small dimensions and more particularly for the compacting of loose sugar to sugar lumps.

A first feature of my invention resides in the fact that, in a machine of the aforementioned kind, the drum is provided with vertically spaced and aligned loose-material-compacting cavities and that the pistons co-operating with each set of vertically aligned cavities are actuated by a common follower running on the central cam.

A further feature of my invention resides in the fact that the cavities once filled with the loose compactable material are shut off during the compression of the latter by means of one single rigid member to which a pendular motion is imparted so that during part of the revolution of the drum it will partake of the rotary movement of the latter and thereby provide a relatively unmovable rest for the material undergoing agglomeration.

Further advantages of my invention will be set forth in the following specification in which reference is had to the drawing appended hereto in which:

Fig. 1 shows the rotary moulding drum with its members.

Fig. 2 shows a section of this member along II—II of Fig. 1.

Fig. 3 shows a section of the drum along III—III of Fig. 1.

Fig. 4 shows a perspective view of the drum provided with its compression platen.

Fig. 5 shows a perspective view of the mounting of the connecting rods and pistons on a slider of the drum.

Fig. 6 shows a longitudinal section of the wiper of the pistons of the drum.

The rotary drum 5 (Figs. 1 and 2) is arranged below a hopper 1 inside which rotary stirrers 2 are adapted to rotate. In the body of the drum 5 are provided radial cavities 3, inside which are adapted to move pistons 4 actuated by connecting rods 7 provided with double knuckle-joints 30 and 31 (see Fig. 5), said connecting rods 55

2

being pivotally connected to a slider 8, the axis of which is parallel to that of the drum. Said slider is adapted to slide inside the drum in a radial slot, and this sliding movement is imparted to it by means of rollers 32 and 33 (Fig. 5) in contact with stationary cams 24, 25 and 26 secured to the frame.

A platen 6 covers a strip of the drum bounded by the bases and by two generators: said platen 10 is pivotally connected to the rod 9 provided with an eccentric 10 (see Fig. 4) or is driven by any other means capable of imparting to it a circular oscillating movement about the shaft 28 of the drum. A mechanism 11 comprising an eccentric and an actuating worm or the like controls the orientation of the cam 25 pivoted at 37. The cam 26, which is pivoted at 38, bears against an abutment 27 which in turn bears against a system of levers 35 and calibrated springs 36 (see Fig. 3). A wad 12 of felt or other fibrous material surrounds a sole 13 shown in longitudinal section in Fig. 6; this sole is subjected to the thrust of adjustable screws 14 that bear against a bar 15 which is parallel to the generators of the drum, said bar being pivotally connected at one end to an eccentric rod 39. A cake 17 of fatty substance in the solid state is pressed against the drum by an adjustable device provided with a retracting spring 16. A scraper 18 made of plastic material is adapted to rub along a generator of the drum.

Pushers 21 forming part of a comb 20 located below the drum are actuated by a cam 34 or by any other reciprocating mechanism. They are arranged horizontally, just above an endless conveyor belt 19 which is adapted to move below the drum.

Operation

The crystallized and moistened sugar fills the hopper 1, and by the combined action of its own weight and of the stirrers 2, fills the cavity 3 (in the position A in Fig. 1), while the drum is rotating (in a counter-clockwise direction in Fig. 1). The cavity then moves in front of the platen 6 which at that instant is oscillating in the direction in which it accompanies the movement of the drum; while the piston 4 compresses the sugar contained in the cavity (position C) against the platen. Owing to this accompanying movement, the platen does not rub against the sugar lump, and the latter is neither glazed nor superficially hardened. The piston 4 is driven by means of the connecting rods 7 by the action of the slider 8, the rollers 33 of which are driven

by the compression cam 26. The slider, which is guided in the drum, moves in a radial half-plane relatively to said drum. A safety device is adapted to prevent a dangerous stress developing on these compression members, which may be caused by the cavity being filled too full of sugar; in this case, the cam 26 overcomes the resistance of the calibrated springs of its abutment 27, retracts by pivoting about its pivot 38 and does not exert a strong force on the slider.

Owing to the shape of the ejecting cam 24, which guides the rollers 32 after the compression stroke, the pistons are slightly retracted so as to become detached from the sugar ingot (position D) and then eject the lump (position E) by moving into a position flush with the outer surface of the drum. The lumps fall at 22 on to plates 23 carried by the conveyor belt 19, by the combined action of their weight, and if desired of the pusher 21 forming part of the comb 20, said comb being adapted to effect a reciprocating movement by means of the end cam 34 (Fig. 2). As the drum continues to rotate, the piston, which is still flush with the mouth of the cavity, moves successively into contact with the sugar scraper 18, the lubricator 17 and the wiper 12, before it is again retracted so as to provide, in the position A, the requisite filling volume. This volume can be adjusted by acting on the mechanism 11 which causes the admission cam 25 to swing about its pivot 37.

The filling cam 25 and the ejecting cam 24 guide both the sides of the rollers 32 located at each end of the slider, whereas the compression cam 26 acts on only one side of one or more rollers 33.

The compression by the cam 26 may be effected in one or more stages, according to the shape of said cam. There may be a single slider for two or more adjacent rows of cavities (two rows in the case illustrated in the figures).

What I claim is:

1. In a machine to compact a loose material to solid lumps having a feeding hopper to be filled with the loose material and a molding drum located below the feeding hopper, a structure of said molding drum comprising a frame, a rotary drum mounted with its axis horizontal in the frame, said drum being bored, on the one hand in its peripheral portion with radial cavities arranged in rows parallel to the axis of the drum, said rows being arranged in a plurality of series of rows around the drum and, on the other hand, in its inner portion with radial slots parallel to the axis of the drum, each of said slots communicating with the radial cavities of one of the series of the rows of the radial cavities, a piston located in each radial cavity, a slide located in each slot, followers carried by said slide inside of the drum, connecting rods having each one end linked to a piston and the other end linked to the slide located in the slot communicating with the radial cavity in which the said piston is located, a cam system on the frame, inside the hollow drum controlling the radial movement of the followers

during the rotation of the drum a movable plate rotatably sliding on the peripheral portion of the drum and covering at least one of the series of the rows of the cavities, and means to impart to said plate a reciprocating movement, a part of said reciprocating movement accompanying the rotation of the drum with substantially the same speed.

2. A structure of molding drum according to claim 1 wherein the cavities are arranged along girdling areas of the peripheral portion of the drum separated by even girdling areas and comprising a fork having parallel prongs arranged horizontally beneath the drum, rectangular to the axis of the drum along the even girdling areas of the peripheral portion of the drum and means causing a reciprocating movement of said fork in a direction parallel to the axis of the drum.

3. A structure of molding drum according to claim 1 wherein the cam system comprises a camway guiding inwardly the followers of each slide that nears the hopper, means to adjust the position of said camway, a cam resiliently pushing outwardly the followers of the same slide when said slide passes beneath the plate during the part of the reciprocating movement of said plate accompanying the rotation of the drum with substantially the same speed, and another camway guiding then the followers of the same slide first slightly inwardly and, thereafter outwardly to a radial position setting the pistons connected to said slide flush with the peripheral portion of the drum when said pistons come at their lowermost position and lastly maintaining said followers in the same radial position until said followers engage anew the first-mentioned camway.

4. A structure of molding drum according to claim 3 comprising piston lubricating means mounted on the frame against the peripheral portion of the drum after the lower part of said drum.

5. A structure of molding drum according to claim 4 comprising piston cleaning means mounted on the frame against the peripheral portion of the drum, between the piston lubricating means and the hopper and means to reciprocate said piston cleaning means.

JEAN LOUIS CHAMBON.
